SQUEEZE BULB FOR SIPHONING AND DISPENSING SHAMPOO OR THE LIKE

Bruno W. Kersten, Chester, Pa., assignor to Marion S. Pump, Kalamazoo, Mich.

Filed Dec. 2, 1959, Ser. No. 58,531

Term of patent 14 years

(Cl. D62—2)

I claim:

The ornamental design for a squeeze bulb for siphoning and dispensing shampoo or the like, as shown and described.
